UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

WINDMILL.

1,155,518.

Specification of Letters Patent.

Patented Oct. 5, 1915.

Application filed April 9, 1914. Serial No. 830,580.

To all whom it may concern:

Be it known that I, DANIEL R. SCHOLES, citizen of the United States, residing at Chicago, in the county of Cook and State of Illinois, have invented a certain new and useful Improvement in Windmills, of which the following is a full, clear, concise, and exact description, reference being had to the accompanying drawings, forming a part of this specification.

10 The invention relates to wind mills and has for its objects the simplification and improvement of wind mill mechanism.

15 The wind mill of my invention includes a wind wheel, a mill vane, a supporting head for said wheel and vane and upon which the vane is mounted to open from and close toward the wheel, a tower terminating at its upper end in an upright tubular column upon which the mill head is mounted to rotate about an upright axis, a coupler disposed about the upright column and movable longitudinally thereof and upon the exterior of the tower structure, this coupler having one member which is rotatable about the column and a second member also disposed about the column and provided with means for substantially limiting it to movement along the column, motion transmitting 20 means between the first aforesaid coupler member and the vane for effecting movement of the vane with respect to the wheel, and motion transmitting means intervening between the second aforesaid coupler member 25 and the lower portion of the tower to enable an attendant to operate the vane, the two motion transmitting means being upon the exterior of the column and mill head.

30 A specific form of the invention, but to which form the invention is not to be limited, is shown by the accompanying drawings in which—

35 Figure 1 generally shows the structure; Fig. 2 shows the upper part more in detail; Fig. 3 is a side view of parts appearing in Fig. 2; Fig. 4 is a plan view; Fig. 5 is an elevation on line 5 5 of Fig. 4; Figs. 6, 7 and 8 show details.

40 Like parts are indicated by similar characters of reference throughout the different figures.

45 The top of tower 1 terminates in an upright stationary tubular column 2 whose reduced upper end constitutes an upright shaft 50 3 affording an upright axis about which the

wind mill head 4 may turn upon a step bearing ring 5 supported upon the lower column portion.

Instead of separately forming and thereafter assembling the tubular portions 2, 3, 60 they are integrally made from a single piece of pipe originally of the diameter of the larger part of the column, the shaft 2 being formed by contracting the upper part of the column, while the lower step bearing carrying part retains its original diameter. The shaft 10 of wind wheel 11 is journaled upon the mill head and carries a pair of upright pinions or gears 12 for driving the upright pump or load rod 13. A pair of upright 70 transmission gears 14 are in mesh with the pinions or gears 12 and are journaled within a bearing 15 carried by the head 4. Pitmen 16 connect gears 14 with the upper end of load rod 13. A stirrup 17 is fixed upon the upper end of the load rod and carries a shaft 18. Stirrup 19 engages and guides roller 20 on shaft 18. The gears 12 are relatively 75 fixed and, to insure the even division of driving power between the two sets of 80 meshed gears and their pitmen, the gears 14 of the other pair are free to move relatively in their planes to compensate for inaccurate alinement of the teeth of either or both pairs of gears. Said gears 14 are therefore provided with shafts 21, 22 that are in telescoping and relatively rotatable relation, the outer sleeve shaft 22 being directly supported by the bearing 15 and itself constituting a bearing for the inner shaft 21 which may 85 also be hollow if desired. Relative end play of the gears 14 is prevented by the inter-engagement of the shafts 21 and 22 shown in Figs. 6 and 7. In the structure of these figures the gear shaft 21 carries an oblong 90 end 21¹ which may be positioned to slip through an oblong continuation 22¹ of the bore of shaft 22 whereafter said shafts are 95 relatively rotated to bring the flat end 21¹ in some such relationship as that illustrated 100 in Fig. 7 and which relationship is substantially maintained by the intermeshing of gears 14 and gears 12.

The mill vane 24 has a stem 25 mounted upon the head 4 to swing about an upright 105 axis. A coil spring 26 connects the mill vane with the extension 4¹ of head 4 and, as shown, operates to maintain the vane open and the wheel 11 in the wind. A lever 27 (Fig. 1) may be operated against the force 110

of spring 26 to close the vane toward the wind wheel to bring this wheel out of the wind. Buffer springs 28 and 29 cushion the vane when moved to closed and open positions respectively.

The larger portion of the stationary column 2 is encircled by a coupler or cross head 31 to which is attached a non-rotating stirrup or other extension 32 that is connected 10 with the upper end of a wire 33 whose lower end is connected with lever 27. A chain or other suitable form of flexible tie member 34 passes over rollers 35 and is connected at its lower end with the coupler and 15 at its upper end with the vane stem 25. When the lever 27 is depressed the stirrup 32 and coupler 31 are drawn downwardly to cause the chain 34 to pull the mill vane to a closed position. Any suitable form of 20 braking mechanism may be employed to check the idle rotation of the wind wheel when out of the wind.

To enable the chain or tie 34 to move bodily with the mill head the lower end of 25 said tie is connected with a ring 42 forming a rotatable part of the coupler. The ring 42 is caused to accompany head 4 in its bodily movement by means of a long finger mill head extension 43 that is in permanent sliding engagement with and between projections 44, formed upon the ring, irrespective 30 of the vertical position of the ring. A brace

45 connects the lower end of the finger with another portion of the head 4 (Fig. 2).

Claims respecting the telescoping arrangement of the gear wheels and pinions are included in my division of this application Serial No. 865,484, filed October 7, 1914.

While there is herein shown and particularly described the preferred embodiment of 40 the invention, the invention is not to be limited to the precise details of construction shown as changes may readily be made without departing from the spirit of the invention, but

Having thus described the invention there is claimed as new the following:—

A wind mill including a wind wheel; a mill head; a supporting tower; and an upright tubular column fixed at the upper end 50 of said tower and having a lower portion upon which the mill head may turn and an upper portion of smaller diameter that constitutes a shaft about which the mill head may turn, said column portions being integrally formed from a single tube.

In witness whereof, I hereunto subscribe my name this twenty third day of March A. D., 1914.

DANIEL R. SCHOLES.
